UNITED STATES PATENT OFFICE

2,561,996

ACETYLENE GENERATION FROM
HYDROCARBONS

Sam P. Robinson, Bartlesville, Okla., assignor to
Phillips Petroleum Company, a corporation of
Delaware

Application August 21, 1947, Serial No. 769,795

8 Claims. (Cl. 260—679)

1

This invention relates to the production of hydrocarbons high in carbon content, i. e., in weight percent of carbon, from hydrocarbons low in carbon content by partial combustion with elemental oxygen or oxygen-rich streams, and more particularly to the production of acetylene from paraffin and olefin hydrocarbons, and to apparatus for producing high yields thereof.

It is known in the art that hydrocarbons may be cracked by partial combustion of low-carbon hydrocarbons with air, but the diluent effect of the nitrogen causes low thermal efficiencies. It has also been proposed to preheat oxygen and hydrocarbons separately and to mix them in a reaction chamber to de-hydrogenate the hydrocarbons at a fixed elevated temperature. The prior methods and apparatus for production of the higher carbon hydrocarbons, for example, acetylene, have been effective for concentrations from 3% up to, in some cases 10% by volume, but higher percentages have not been attained and impurities have been formed which are difficult of removal.

Among the objects of the present invention are the continuous production of high-carbon hydrocarbons in high concentration, for example, in excess of 20% of the volume of the initial hydrocarbon; more efficient operation of the required apparatus; independent heating means for the hydrocarbon and the oxygen, and a cooperative relationship between the various zones of the hydrocarbon reaction chamber or chambers and the oxygen heating apparatus. Further advantages of the invention are successively more rapid reaction times as the reaction progresses, successive introduction of oxygen at higher temperatures, decreased partial pressures of the reaction hydrocarbon at successive stages in the reaction, and automatic introduction of oxygen at progressively higher temperatures at intermediate progressive stages of the reaction cycle.

While the invention is particularly adapted to the production of acetylene from paraffin hydrocarbons such as ethane, it is to be understood that other hydrocarbons may be used as the starting materials or as intermediates, including olefins such as ethylene. It is also to be understood that the invention is applicable to the production of olefins from paraffins; for example, ethylene, from ethane; although the most advantageous use of the invention at present, for economic reasons, is in the manufacture of acetylene on a commercial basis at extremely low cost.

In practicing the invention, ethane is first preheated by suitable means and introduced, to-

2

gether with free oxygen which has also been preheated, into a reaction chamber containing small pebbles of aluminum oxide which effect thorough dispersion and mixture of the ethane and the oxygen. Each of the reaction chambers contains a fixed bed of refractory pebbles. It is preferred that the ethane be heated to between 1000 and 1500° F. prior to introduction into the first reaction chamber, and that the oxygen be preheated to a temperature within the range of 700 to 1000° F. The effluent from the first reaction chamber, which comprises relatively high concentration of ethylene is then mixed with additional oxygen which has been preheated to a higher temperature than the initial oxygen, for example from 1000 to 1500° F. The mixture containing the additional increment of preheated oxygen is then introduced into a second reaction chamber and partial combustion takes place at a higher temperature, for example 2000 to 2500° F. and for a shorter period of time than the initial reaction. The reaction in the first chamber may occur in 0.5 second at a temperature between 1500 and 2000° F., whereas the reaction in the second chamber may occur in a period of time which is about one-fifth that of the first, e. g., 0.10 second. The reaction may be caused to progress in one or more subsequent reaction chambers by the introduction of additional oxygen heated to an even higher temperature, for example, 2,000° F. to 2,500° F. This additional increment of oxygen may be mixed with the effluent in a mixing bustle and the admixture introduced into an even smaller reaction chamber having a temperature in excess of 2,500° F., this reaction taking place in a considerably reduced period of time, of the order of 0.02 second. Further reaction stages may be carried out, if desired, but it has been found that the concentration of acetylene thus produced from ethane in the effluent of the third reaction chamber is in excess of 20% by volume.

The final effluent containing the acetylene in high concentration is then cooled, for example, by a quenching spray of water or other quenching medium, to a temperature at which the acetylene may be recovered without further reaction, and the impurities are removed in conventional manner.

While any desired heating means may be used for progressively raising the temperature with the increments of oxygen, it has been found highly desirable and economical to provide a heating chamber, or preferably a series of heating chambers through which the oxygen is passed in the

direction of the source of heat. The source of heat is preferably a continuously travelling quantity of heating elements which pass through the oxygen heater or series of heaters countercurrently to the flow of oxygen therethrough. It has been found convenient to use refractory pebbles as the heating elements and to pass them downwardly through a vertically arranged series of heating chambers while passing the oxygen upwardly through the chambers, thereby providing the highest temperatures for the oxygen in the uppermost heating temperature and the lowest temperatures at the bottom of the stack, the intermediate volumes of oxygen being progressively hotter as the oxygen is forced upward. When this arrangement is used for the heater, it is particularly convenient to similarly stack the reaction chambers with the first and largest volume chamber at the lowermost position and the last and smallest chamber at the uppermost position. In accordance with this invention it is preferred to arrange the oxygen heating chambers opposite the respective reaction chambers to which the oxygen at the various temperatures is to be introduced, thereby avoiding heat losses and excessive lengths of the conduits leading from the heaters to the reaction chambers.

Referring to the drawing, which is a diagrammatic representation, the hydrocarbon is preheated by introducing gaseous or liquid fuel and air through the conduit 1 into a mixing chamber 2 and thence through conduit 3 into a preheater 4. Hydrocarbon is introduced at 5 through a coil 6 within the preheater and thence through conduit 7 to a hydrocarbon distributor 8. While a specific method and apparatus are described for the preheating of the hydrocarbon, it is of course understood that any other suitable means may be used. The preheated hydrocarbon is then fed or forced into a mixing bustle 9 together with preheated oxygen from conduit 10 into the first reaction chamber 11 wherein thermal pyrolysis causes partial dehydrogenation of the hydrocarbon, such as ethane, thereby effecting a high yield of ethylene. The effluent gases from chamber 11 at elevated temperature are mixed in a second mixing bustle 12 with oxygen introduced at the conduit 13 at higher temperature than the oxygen from conduit 10. The mixture is then forced into a smaller reaction chamber 14 heated to a higher temperature than chamber 11, wherein the reaction takes place in a shorter time and the effluent is mixed in a third mixing bustle 15 with still hotter oxygen introduced from conduit 16. The mixture from the bustle 15 then passes into a still smaller reaction chamber 17, wherein further partial combustion takes place at a higher temperature than either of the two preceding reactions. The effluent from the reaction chamber 17 has a high acetylene content, i. e., over 20% by volume, and is withdrawn through conduit 18, and quenched by a fluid from conduit 19 such as a direct spray of water or other quenching medium, whence it emerges at 20.

As the gases pass from the first to the last reaction chamber, the partial combustion takes place at increasingly higher temperatures in the presence of increasing amounts of hydrogen, steam and carbon oxides which effectively depress the partial pressure of the hydrocarbon reactant to insure higher yields of acetylene. The higher yields are also assisted by the decreasing size of the successive reaction chambers, as well as by the decreasing periods of time for the successive reactions. It is of course desirable to insulate

the elements of the entire system including the conduits.

At the same time that the reaction is progressing, oxygen introduced at conduit 21 is forced through a series of heating chambers 22 and 23 at successively higher temperatures. The heating is effected by first introducing refractory pebbles through the conduit or chute 24 into a pebble heating chamber 25 which may be heated by introducing fluid fuel and air through conduit 26. After the pebbles are heated they descend from the heating chamber 25 through a conduit 27 into chamber 23, where they are partially cooled by the influx of oxygen therethrough which enters through line 13, and thence through conduit 28 into chamber 22 to heat the initial oxygen to a relatively lower temperature. The pebbles are removed through conduit 29 from the bottom of chamber 22 and are mechanically reintroduced along the path 30 back up to the chute 24 and into the heating chamber 25 to commence another heating cycle. The stack gases from combustion of the fuel in chamber 25 are vented at conduit 31. The lower-temperature oxygen is withdrawn from chamber 22 through conduit 32 and is branched into conduits 10 and 13. A portion of the preheated oxygen from conduit 32 is mixed with higher-temperature oxygen from conduit 33, thus yielding an oxygen feed at 13 of intermediate temperature. The hottest oxygen, from conduit 33, is in part introduced into the mixing bustle 15 through conduit 16.

The conduits leading from the oxygen heating chambers to the mixers for the reaction chambers are preferably arranged in straight lines in order to reduce heat losses which would be occasioned by circuitous paths.

While a vertical arrangement is shown in the drawing for the heating chambers and the reaction chambers, and a gravity flow system for the heating elements is shown for the heating pebbles, it is to be understood that other arrangements may be employed without sacrificing the advantages of the invention.

As a specific example of practicing the invention, three parts by volume of 95% ethane are preheated to 1,200° F. and then mixed in a bustle 9 with one part of oxygen heated to 800° F. from heater 22. The resulting mixture is then passed through a fixed pebble bed in the reaction chamber 11 maintained at 1,650° F. by partial combustion of part of the ethane and cracked products. The effluent contains in excess of 30% by volume of ethylene and is then further cracked successively in the reaction chambers 14 and 17 at increasing temperatures, in reduced reaction times and in the presence of increasing partial pressures of hydrogen, steam, and carbon monoxide by incremental additions of increasingly hot oxygen from the conduits 13 and 16. Reaction times in the successive chambers are 0.5 second, 0.1 second, and 0.02 second, and the respective temperatures at which the pebbles in each of the reaction chambers are maintained are 1,500-2,000° F., 2,000-2,500° F., and about 2,600° F. The respective temperatures for the oxygen introduced through conduits 10, 13, and 16 are approximately 800° F., 1,250° F., and 2,000° F. The acetylene emerging from the conduit 18 at the top of the stack of reaction chambers is in volumetric concentration in excess of 20%. The effluent including acetylene, steam, and carbon oxides is then quenched down to a safe temperature and the impurities are removed in conventional manner.

In view of the many changes and modification that may be made without departing from the principles underlying the invention, reference should be made to the appended claims for an understanding of the scope of the protection afforded the invention.

What is claimed is:

1. The process of producing acetylene which comprises, separately preheating reactant hydrocarbon low in carbon content and oxygen, the total amount of oxygen being stoichiometrically insufficient for complete combustion of the reactant hydrocarbon, the oxygen being heated to a temperature below that of the reactant hydrocarbon, mixing the reactant hydrocarbon and oxygen in a first mixing zone of restricted cross section, passing the mixture through a first reaction zone having a cross-sectional area and volume substantially greater than said first mixing zone, admixing the gaseous effluent from said first reaction zone in a second mixing zone of restricted cross section with additional oxygen preheated to a temperature higher than that of said first-mentioned oxygen, but lower than the temperature of the reactant gases, passing the resulting mixture through a second reaction zone having a cross-sectional area and volume less than said first reaction zone but greater than said second mixing zone, admixing the gaseous effluent from said second reaction zone in a third mixing zone of restricted cross section with additional oxygen preheated to a temperature higher than that of said second-mentioned oxygen, but lower than the temperature of the reactant gases, passing the resulting mixture through a third reaction zone having a cross-sectional area and volume less than said second reaction zone but greater than any of said mixing zones, quenching the resulting effluent from said third reaction zone and recovering acetylene as a product of the process.

2. The process in accordance with claim 1 in which the reactant hydrocarbon is ethane.

3. The process in accordance with claim 1 in which the reactant hydrocarbon is ethylene.

4. The process of producing acetylene which comprises separately preheating reactant hydrocarbon and oxygen, the total amount of oxygen being stoichiometrically insufficient for complete combustion of the reactant hydrocarbon, the oxygen being preheated to 700° to 1000° F., mixing the reactant hydrocarbon and oxygen in a first mixing zone of restricted cross section and passing the mixture through a first reaction zone having a cross-sectional area and volume substantially greater than the first mixing zone where the first partial combustion is carried out at about 1000° to 1500° F., admixing the gaseous effluent from said first reaction zone in a second mixing zone of restricted cross-section with additional oxygen preheated to about 1000° to 1500° F., passing the resulting mixture through a second reaction zone having a cross-sectional area and volume less than said first reaction zone but greater than said second mixing zone, wherein the partial combustion is carried at about 2000° to 2500° F. admixing the gaseous effluent from said second reaction zone in a third mixing zone of restricted cross-sectional area with additional oxygen preheated to a temperature of about 2000° to 2500° F. and passing the resulting mixture through a third reaction zone having a cross-sectional area and volume less than said second reaction zone, but greater than any of said mixing zones and accomplishing the partial combustion in excess

of about 2500° F. and quenching the resulting effluent from said third reaction zone and recovering acetylene as a product of the process.

5. The process in accordance with claim 4 in which the reactant gas is ethane.

6. The process in accordance with claim 4 in which the reactant gas is ethylene.

7. The process of producing acetylene which is characterized by the partial combustion of reactant hydrocarbon gas in at least three stages in progressively smaller reaction zones at progressively higher temperatures, comprising, separately preheating the reactant hydrocarbon gas and an amount of oxygen stoichiometrically insufficient for complete combustion, the oxygen being preheated to a lower temperature than the reactant hydrocarbon, passing said oxygen and reactant hydrocarbon into a reaction zone and accomplishing partial combustion of said reactant hydrocarbon in said reaction zone, thereby inducing some temperature rise therein and repeating said preheating of oxygen and partial combustion of said reactant gases at successive substantial increments of temperature, and finally quenching said reactant gases to recover acetylene therefrom.

8. The process of producing acetylene which comprises separately preheating reactant hydrocarbon having two carbon atoms and oxygen, the total amount of oxygen being stoichiometrically insufficient for complete combustion of the reactant hydrocarbon, the oxygen being preheated to 700° to 1000° F., mixing the reactant hydrocarbon and oxygen in a first mixing zone of restricted cross section and passing the mixture through a first reaction zone having a cross-sectional area and volume substantially greater than the first mixing zone where the first partial combustion is carried out at about 1000° to 1500° F., admixing the gaseous effluent from said first reaction zone in a second mixing zone of restricted cross section with additional oxygen preheated to about 1000° to 1500° F., passing the resulting mixture through a second reaction zone having a cross-sectional area and volume less than said first reaction zone but greater than said second mixing zone, wherein the partial combustion is carried at about 2000° to 2500° F. admixing the gaseous effluent from said second reaction zone in a third mixing zone of restricted cross-sectional area with additional oxygen preheated to a temperature of about 2000° to 2500° F. and passing the resulting mixture through a third reaction zone having a cross sectional area and volume less than said second reaction zone, but greater than any of said mixing zones and accomplishing the partial combustion in excess of about 2500° F. and quenching the resulting effluent from said third reaction zone and recovering acetylene as a product of the process.
